UNITED STATES PATENT OFFICE.

LEVI WESTINGHOUSE, OF ST. LOUIS, MISSOURI.

TRUSS.

SPECIFICATION forming part of Letters Patent No. 236,922, dated January 25, 1881.

Application filed October 2, 1880. (Model.)

To all whom it may concern:

Be it known that I, LEVI WESTINGHOUSE, of St. Louis, in the county of St. Louis and State of Missouri, have invented certain new and useful Improvements in Trusses; and I do hereby declare that the following is a full, clear, and exact description of the invention, which will enable others skilled in the art to which it appertains to make and use the same, reference being had to the accompanying drawings, which form a part of this specification.

Figure 1 is a view, in perspective, of a truss provided with my improvements. Fig. 2 is an internal view of the back plate of the pad. Fig. 3 is a vertical sectional view of the pad and pad-frame. Fig. 4 is a rear view of the truss. Fig. 5 is a perspective view of the fastening or clasp by which the truss is adjusted to the wearer. Fig. 6 is a longitudinal sectional view vertically of the fastening, and Fig. 7 is a perspective view of the securing-wedge.

This invention has relation to trusses; and it consists of the improved features of construction and combination hereinafter fully described, and particularly pointed out in the claims.

Referring by letter to the accompanying drawings, A A' designate the waist-straps; B, the back piece or pad, and C the strap which is passed between the limbs of the wearer.

The pad-frame is constructed of two metal plates, D D', secured together by screws E, to form a chamber, F, in which is placed the spring G, bearing against a stud, H, at one end, and a notched projection, I, of a pivoted arm, J, at the other.

K designates a slide working in ways L on the under face of the back plate, D', of the pad-frame, having a stud, M, on its upper face, which projects through a slot, N, in the plate D'. The back plate, D', is also provided on its upper face with studs P P' P²—the former for the reception of the loops Q upon the straps R R', by which the connection is formed between the pad and the waist-strap A, and the loop upon the strap S fastened to the waist-strap A'. Rivets are used to connect the loops to the straps R, S, and T, the latter extending from the back piece along the outer face of the strap C through a loop, U, at the end of C.

The metal loop V is passed over the stud M, and when the truss is in place on the wearer the yielding stud M regulates the tension on the strap C, causing it to take up the slack occasioned by a change of position on the part of the wearer, the tendency of the stud M being in the direction of the top of the slot N. Buttons W are secured upon the studs M, P, P', and P² by screws X, driven through said buttons W into the shanks of the said studs. The slide K is connected to the pivoted arm J by an auxiliary arm, Z.

The fastening or clasp employed in this truss, in lieu of the ordinary buckle, consists of a wedge-shaped or tapering sheath, A², through which the connecting-straps are passed, and are held in place therein by a wedge, a, having a shoulder, b, upon its upper face at its point, and a recess, c, and a transverse flange, d, on its under face. The under face of the sheath A² is provided with a stud and button, e, by which it is fastened to the strap or back piece of the truss, as the case may be. The wedge is placed upon the embossed face of the small straps used to connect and adjust the several parts of the truss, the wedge a being inserted in the sheath, with the shoulder b against the forward edge of the sheath A². The strap is inserted from the smaller end of the sheath A² and is passed back the required distance. When any forward strain comes upon the strap the wedge a will move forward in the sheath A², and the flange d will bind the strap and hold it after it has moved a very short distance in the sheath. The end of the strap which passes between the limbs of the wearer is connected to the sliding stud M, which has a tendency at all times to seek the upper end of the slot N, so that the strap, which, when first connected, draws the stud M away from the upper portion of the slot N, will have a uniform tension if, by a change in the position of the wearer, it should slacken, as the spring would operate the yielding stud and take up the slack. This construction permits the pad to be always held to place while being worn. The straps do not need to be weakened by punching holes for the buckle-tongue, and the clasps may be adjusted more accurately than where the ordinary buckle is employed.

The truss is simple, durable, and no more expensive than those ordinarily used, and the construction and operation will be readily understood by reference to the drawings, when taken in connection with the foregoing description.

Having thus fully described my invention, what I claim as new, and desire to secure by Letters Patent of the United States, is—

- 10 1. In a truss, the pad-frame provided with the yielding stud working in a slot in the back plate of said frame, and held to its normal position when disconnected from its strap by the spring G, constructed and operating substantially as and for the purposes set forth.

2. In a truss, the pad-frame having its back plate provided with studs P P' P'', upon which removable buttons are secured by screws passed through said buttons into the shanks of the studs, substantially as and for the purposes set forth.

In testimony that I claim the foregoing as my own I have hereto affixed my signature in presence of two witnesses.

LEVI WESTINGHOUSE.
